GLOVE

Elias Breath, New York, N. Y.

Application November 9, 1950, Serial No. 12,930

Term of patent 3½ years

(Cl. D3—11)

To all whom it may concern:

Be it known that I, Elias Breath, a citizen of the United States of America, residing in New York city, county of Kings, and State of New York, have invented a new, original, and ornamental Design for a Glove, of which the following is a specification, reference being had to the accompanying drawing, forming part thereof, wherein,

I claim:

The ornamental design for a glove, substantially as shown.

ELIAS BREATH.
